UNITED STATES PATENT OFFICE.

JOHN SCHIES, OF ANDERSON, INDIANA.

JAR-CLOSURE.

SPECIFICATION forming part of Letters Patent No. 674,713, dated May 21, 1901.

Application filed February 13, 1901. Serial No. 47,132. (No model.)

To all whom it may concern:

Be it known that I, JOHN SCHIES, residing at Anderson, in the county of Madison and State of Indiana, have made certain new and 5 useful Improvements in Jar-Closures, of which the following is a specification.

My invention is an improvement in closures of jars and the like, and has for an object to provide a jar-closure which will be secure 10 and easily applied and removed; and the invention consists in certain novel constructions and combinations of parts, as will be hereinafter described and claimed.

In the drawings, Figure 1 is a perspective 15 view of the invention as in use, the parts being shown in sealed position. Fig. 2 is a longitudinal section of the closure, the depending wing of the cap-securing ring being free of engagement with the downwardly-facing 20 shoulder of the bottle-neck. Fig. 3 is a similar section with the said wing pressed into engagement with the shoulder. Fig. 4 is a detail perspective view of the cap-securing ring.

25 The jar may be formed in any suitable design and has its neck A provided within its mouth and below its lip B with an upwardly-facing shoulder C, while the outer side of the neck is provided below its lip with a downwardly-facing shoulder D, as best shown in 30 Figs. 2 and 3. Within the neck I fit a lining-disk E, which may be of cork, felt, glass, or other suitable material and which rests upon the shoulder C and fits snugly within the neck 35 above the said shoulder. The disk E, when made of cork, felt, or other readily-compressible material, will in the sealed position of the parts, as shown in Fig. 3, be pressed up into the concave under side of the cap F.

40 This cap F is provided on its under side with the depending portion F', which fits within the neck of the jar and bears upon the disk E above the shoulder C, the under side of the cap F within the area of the portion F' being preferably dished or concave at F², as 45 shown in Figs. 2 and 3. The cap F is also provided with a portion F³, which projects laterally beyond the portion F' and overlies the lip B of the jar. In its upper side, at its 50 edge, the cap F is provided with a groove or rabbet F⁴.

A gasket G is fitted between the lip of the

jar and the projecting portion F³ of the cap F. This gasket also encircles the depending portion F' of the cap and fits within the depending wing H² of the ring H. This ring H is shown in detail in Fig. 4 and comprises a horizontal top wing H', which fits within the rabbet F⁴ in the top of the cap, and the depending wing H², which extends down alongside of and below the cap F and down alongside the jar-neck to a point below the shoulder D, as shown in Fig. 2. When the parts are adjusted, as shown in Fig. 2, to close the jar, it will be noticed the several parts are 55 held securely in position, as the cap maintains the lining-disk in place and the gasket is held between the portion F' of the cap and the wing H² of the ring and between the lip of the jar and the portion F³ of the cap. In 60 the lower edge of the wing H² are formed a number of V-shaped notches H³, which separate the lower edge of the wing into a number of sections which are bent squarely beneath the shoulder D and in practice is rolled up 65 tight against the said shoulder with small rollers, drawing the ring downward and causing it to press the cap firmly upon the gasket G and the lining-disk, thus securing an airtight closure. The V-shaped notches may be 70 increased in number to any desired extent, and the ring can be readily released by bending back the portions h, which are bent beneath the shoulder D, as shown in Figs. 1 and 3.

Having thus described my invention, what 75 I claim, and desire to secure by Letters Patent, is—

1. A closure substantially as described, comprising a jar or the like having its neck provided within its mouth below its lip with 80 an upwardly-facing shoulder, and having its neck provided below its lip with an exterior downwardly-facing shoulder, the liner-disk fitted upon the interior upwardly-facing shoulder, the cap rabbeted in its upper face 85 at its edge, provided on its under side with a downwardly-projecting portion fitted to the bottle-neck and resting therein upon the lining-disk, and also having a laterally-projecting portion overlying the lip of the jar, the 90 gasket between said portion of the cap and the lip of the jar, and the fastening-ring having a top wing fitted in the top rabbet of the cap, and the depending wing notched at intervals 95 100

- in its free edge and having such edge between the notches bent inwardly beneath the exterior downwardly-facing shoulder of the neck substantially as set forth.
- 5 2. In a closure substantially as described the combination of the jar having its neck provided on its outer side with a downwardly-facing shoulder, the cap fitting on said neck and the continuous unbroken cap-securing ring having at its upper edge an inwardly-projecting flange overlying the outer edge of the cap and extending inwardly beyond the inner line of the external downwardly-facing shoulder, the body of the ring being fitted 10 snugly around the neck of the jar and having at its lower edge portions bent beneath the shoulder of the jar-neck and arranged to be bent outward to release the closure substantially as set forth.
- 15 3. In a closure the combination of the jar

having its neck provided with an external downwardly-facing shoulder, the cap resting at its outer edge upon the neck of the jar and coinciding at such edge with the outer surface of the jar-neck and provided in its upper 25 face at its outer edge, in a line overlying the neck of the jar, with an annular groove or rabbet which extends inwardly beyond the inner line of the external downwardly-facing shoulder, and the cap-securing ring having at 30 its upper edge an inwardly-projecting flange extending above the neck of the jar and resting in the rabbet of the cap, and having its lower edge bent into locking engagement with the shoulder of the jar substantially as set 35 forth.
